SELF-COMPENSATING ACCUMULATOR

Robert E. Snyder, Pasadena, Calif., assignor to
 Snyder Oil Tool Corporation, Los Angeles,
 Calif., a corporation of California

Application June 7, 1947, Serial No. 753,176

22 Claims. (Cl. 138—31)

1

My invention relates generally to hydro-pneumatic accumulators for reducing and cushioning the shock effects produced by surges of liquid and pressure vibrations in hydraulic systems. More particularly, my invention relates to means used in connection with such accumulators to automatically adjust the same for optimum operation over a wide range of average working pressures in a hydraulic system.

Hydro-pneumatic accumulators are often constructed in the form of a closed container filled with gas under a predetermined pressure, said container being placed in communication with the hydraulic system to be protected whereby sudden changes in the hydraulic pressure are cushioned by compression of the gas in the gas chamber of the accumulator. Furthermore, it is common practice to place movable separatory means between the liquid of the hydraulic system and the gas contained in the accumulator in order to prevent absorption or occlusion of the gas in the liquid, and to avoid other undesirable effects.

Various separatory means such as diaphragms, pistons, bags and combinations of these elements have been used in accumulators of previous construction; for example, in my copending application for United States Letters Patent, Serial No. 710,490, filed November 18, 1946 and entitled "Accumulator," I disclose and claim novel separatory means for the purpose above described.

For the purposes of this disclosure, the following terms and designations will be used.

The average hydraulic line pressure will be designated as P , with various different average pressures being designated as P_1 , P_2 , etc.

The initial pressure of the gas in the accumulator before commencing the operation of the hydraulic system will be termed the "precharge pressure" and will be designated as P_{pr} .

Changes in line pressure above and below the average line pressure P will be designated as p' . In normally operating hydraulic systems this variation p' in the average line pressure P may run to a thousand (or more) pounds per square inch and can be readily recorded on various standard type pressure recorders. For purposes of calculation, the pressure variation p' is usually noted in its relation to P as a certain percentage thereof.

Pressure variations p' are usually occasioned in the line by fluctuating movement of the hydraulic fluid or by shock waves set up therein from the pump, valves, or the operating equipment. The output from a reciprocating pump

is non-uniform, because the velocity of the piston is cyclically non-uniform in both power and steam piston pumps such as are commonly used. Thus while a given pump has an average discharge rate per cycle, the piston movement actually causes a variation in the discharge over the time for a given cycle during which it varies from some value below to a value above, and back to a value below the average discharge rate. This variation in fluid output into the line results in periodic pressure variations p' as the fluid is alternately rammed into or starved from the line at a rate respectively greater or less than the average flow rate. The amount of fluid produced per cycle in excess of the average flow rate has been termed "surge volume" and is designated by the letter S . Obviously the value of S for any given positive displacement pump remains a near constant over its normal pressure operating range. Any accumulator used to absorb and dissipate hydraulic surge should absorb and hold this surge volume S of fluid without raising p' above a predetermined value, and then feed it back into the system in the low points on the pump output to maintain the average flow rate as nearly constant as possible during the pump cycle. Such control of fluid volume produced per cycle results in a corresponding control of p' to maintain the average P within a predetermined range.

Other sources of pressure variation in a hydraulic system are valves, line bends, and operating equipment which give rise to fluid surges and hydraulic vibration. In some cases the frequency will be high and in other cases only a single slow surge due to moving fluid inertia as when a valve is closed. In any case, the gas volume V should absorb and cushion the vibration or the surge. When the frequency is very high the inertia of the absorbing means must necessarily be as low as possible, whereas when the surge is slow, an appreciable time may be utilized to fully absorb it. The maximum surge volume S from a double-acting duplex pump running at about 60 R. P. M. requires approximately one-fifth of a second to move into the accumulator and the line sizes should be constructed to pass such flow rates without substantial back pressure.

For a complete understanding of my invention certain relationships between the foregoing factors should be noted. As mentioned, the fundamental purpose of any accumulator is to maintain p' , or the shock-producing pressure variations, always below that predetermined value

which will produce harmful effects in the system. The optimum value of p' will, of course, be different for various hydraulic systems, but it can be determined for any particular system either by experiment or by calculation.

Given the allowable value of p' and a constant value of S for any given hydraulic system, the volume V of the gas chamber is fixed. For example, let the desired p' equal 5% of P_1 . The fixed value of V is then determined by Boyle's law as follows:

$$P_1 V_1 = P_2 V_2$$

$$P_2 = P_1 + p' = 1.05 P_1$$

$$V_1 = 1.05 V_2$$

$$V_2 = V_1 - S$$

$$\therefore V_1 = 1.05 (V_1 - S), \text{ and } V_1 = 21S$$

This $S:V$ relationship is true regardless of the average working pressure in the hydraulic system, providing of course, that said working pressure is initially balanced by a suitable precharge pressure in the gas chamber of the accumulator.

Since the surge volume S is usually dependent upon the physical dimensions of a pump or similar element in the hydraulic system, and since liquids can be considered as incompressible, the value of S can, as previously stated, be considered as a constant for a given pump over a considerable range of average working pressures P .

If an accumulator is to adequately protect a hydraulic system which may be operated over a wide range of working pressures, it is necessary to change the precharge pressure every time the working pressure is changed in order to maintain the $S:V$ ratio within allowable working limits. Such a procedure is, in many cases, impractical since in most hydraulic systems such, for example, as mud circulating systems used in connection with rotary well drilling equipment, the working pressures vary over a wide range, and often unexpectedly. Thus accumulators which are intended for use in connection with a widely varying average working pressure should incorporate means to automatically adjust and maintain the initial or precharge pressure P_{pr} in the gas chamber substantially equal to the hydraulic working pressure at all times and in a manner which will assure that the ratio of surge volume to gas volume does not exceed a predetermined value, thus keeping the pressure variations p' below their allowable upper limit at all times.

The mode of operation just described may be termed broadly "automatic adjustment of precharge pressure" or "self-compensation," and it is with this phase of accumulator design that the present invention deals.

One object of my invention is to provide a hydro-pneumatic accumulator in which the gas precharge pressure is readily and quickly adjusted to equal that of the average working pressure in the hydraulic system.

Another object of the invention is to provide means for automatically adjusting the above described precharge pressure in direct response to variations in the average line pressure.

A further object is to provide pressure compensating means which can be adapted for use with various kinds of conventional accumulators.

Still another object of my invention is to provide self-compensating accumulator means of the class described which is assembled from sub-assembly units, one of which is designed to pro-

vide optimum protection against surge pressures occasioned by the particular surge volumes S , in a given hydraulic system, and another of which is designed to provide suitable precharge pressure adjustment over the desired range of average working pressures in said system.

A further object is to provide an accumulator of the class described in which the size of parts which may be subject to excessive wear is kept to a minimum with said part being easily replaceable.

The foregoing and other objects and advantages of my invention will become apparent from a consideration of the following description of accumulator structures embodying my invention.

Briefly described, my invention as illustrated herein is embodied in a hydro-pneumatic accumulator comprised of two assemblies, one of which may be a substantially conventional accumulator designed in accordance with the surge volume to be protected against, and taking into consideration the frequency of said surges. This first unit will be referred to as the surge control section or unit.

25 The other unit or assembly of the accumulator embodying my invention is connected to the surge control unit by a gas line to the gas chamber thereof and by a hydraulic line to the hydraulic system in which the accumulator is incorporated. 30 The other unit is referred to herein as the precharge pressure control unit or pressure compensator, two embodiments of which are illustrated and described.

In one form, the precharge control unit is comprised of a relatively large volume cylinder having movable separatory means such as a piston therein. The interior of the cylinder is thus divided by the separatory means into two compartments; one compartment is communicated 40 through a restricted passage to the hydraulic system, and the other compartment through a similar passage with the gas chamber of the surge control unit. The effect of this arrangement is that the piston in the precharge control 45 unit moves in the cylinder (relatively slowly because of said restrictions) compressing the gas on one side of said piston until the piston occupies a position wherein the gas pressure and hydraulic pressure operating thereon are equal. 50 Due to the restrictive communication between the precharge control unit and the hydraulic system, the piston in the precharge unit is relatively unaffected by the surge responsive pressure variations p' , these being cushioned by the operation 55 of the surge control unit.

The second embodiment of the precharge control unit described herein includes a slide valve operating in response to the pressure in the hydraulic system and controlling the delivery of gas under relatively high pressure to the gas chamber of the accumulator. This second arrangement is such that when the working pressure in the hydraulic system reaches a value greater than the then precharge pressure in the accumulator, the valve is operated to admit gas from a gas bottle into the gas chamber of the accumulator, thus bringing the precharge pressure up to a value equal to that of the hydraulic system. If, on the other hand, the working pressure in the hydraulic system drops, the valve is operated in a different direction to release gas from the chamber in the accumulator, thus to bring the precharge pressure down to the value in the hydraulic system.

70 The two units making up my novel accumu-

lator structure can be combined in various ways and several possible arrangements are illustrated and described.

For a more detailed description of the various embodiments of my invention, reference should now be had to the attached drawings in which:

Figure 1 is a diagrammatic elevational section of an accumulator system embodying my invention;

Figure 2 is a partially sectioned elevational view of an actual structure embodying the principles illustrated in Figure 1;

Figure 3 is a partial elevational section illustrating a modified form of a surge control unit such as may be employed in Figure 2;

Figure 4 is a plan view partially sectioned illustrating an "in line" arrangement of the elements illustrated schematically in Figure 1; and,

Figure 5 is a diagrammatic partially sectioned elevational view illustrating a modified form of an accumulator system embodying my invention.

Referring now to Figure 1, a diagrammatic illustration of one form of my invention, it will be seen that I have indicated the surge control unit generally by the number 10, and the precharge pressure control unit by the number 11. The surge control unit 10 is of generally cylindrical shape, being comprised of an upper cylindrical chamber 21 and a relatively short lower cylinder 20. The walls of the lower cylinder 20 are bored, honed, or otherwise machined to provide a smooth operating surface to receive a movable piston 14. The piston 14 is provided with packing rings 15 so as to form a relatively fluid-tight separation between the lower chamber 20 and the upper chamber 21. As indicated in Figures 1 and 2, the piston 14 is free to move vertically somewhat, being limited at the lower end by the bottom of the cylindrical chamber 20, and at the upper end of its movement by a stop ring 19 fixed into the wall of the cylinder 20. However, its total possible stroke is relatively short.

Since the piston 14 never enters the upper chamber 21, the inner walls thereof may be left unmachined, thus minimizing the amount of honing required in the surge unit.

The lower compartment 20 is communicated with the hydraulic system to be protected by means of a conduit 27 connected at opening 25 to the output of the pump or similar element (not shown) in the hydraulic system. In the present instance, the flow of the fluid through the hydraulic system is "in" at the opening 25 and "out" at the opening 27, passing through a screening device 26. Thus the surges in the liquid passing through the hydraulic system are directed in ram fashion through the conduit 27 directly to the surge control unit 10.

The volume 13 of the upper chamber 21 is pre-calculated so that its relationship with the volume S of the surges in the hydraulic system is such that the pressure variation p' will always be less than the predetermined harmful amount.

Mounted within the piston 14 is a flexible cup-shaped diaphragm 16 which is limited in its movement by an upper perforated plate 18 and a lower perforated web 17 in the piston 14. The volumetric capacity of the cup-shaped diaphragm 16 should be at least equal to and preferably greater than the surges S to be absorbed. Thus when the precharge pressure P_{pr} in the upper compartment 21 is equal to the average working pressure in the hydraulic system, the surges are cushioned by alternate collapsing and expand-

ing of the diaphragm 16, which in turn alternately compresses the gas in the compartment 21. Due to the vibratory action of the diaphragm 16 which is caused by the surges in the hydraulic system, the piston 14 will, when the precharge pressure is properly balanced against the hydraulic pressure, assume an intermediate position between the stop ring 19 and the lower end of the chamber 20. The piston will come to rest in this intermediate position and substantially the entire surge motion will be taken up by motion of the diaphragm 16.

It will be remembered that the cushioning effect of the gas in the chamber 21 is fully effective only so long as the precharge pressure P_{pr} is substantially equal to the average hydraulic pressure and the ratio of S to V does not exceed the allowed maximum. For practical purposes, however, it is often necessary to contemplate a considerable range of average working pressures, while the volume of the surges from a given pump remains relatively uniform regardless of the average working pressure.

To accomplish automatic adjustment of the precharge pressure P_{pr} I have provided the pressure compensating unit 11, which is connected by means of ducts 30 and 31 to the gas chamber 21 of the surge control unit and by ducts 28 and 29 to the hydraulic system, the latter connection being made at the conduit 27. In the embodiment illustrated diagrammatically in Figure 1, the pressure compensator 11 is comprised of a cylinder 11a having smooth inner walls 40 and having a movable piston 41 positioned therein. The piston 41 is provided with packing rings 42 whereby the piston separates the pressure adjusting unit 11 into two compartments 43 and 44. The uppermost 43 of these compartments is a gas chamber and is in communication as previously described with the gas chamber 21 of the surge control unit 10. The lower compartment of the precharge pressure adjusting unit 11 is a hydraulic fluid chamber and is, as previously described, connected to the hydraulic system at the conduit 27. Thus it will be seen that the piston 41 provides a movable separatory means between the gas chamber 43 and the fluid chamber 44 of the precharge pressure adjusting unit 11.

The desired restrictions in communication between the unit 11 and the hydraulic line and surge control gas chamber are conveniently provided by restrictive orifices 32 and 33 connected in the liquid and gas ducts 28-29 and 30-31, respectively. In the present instance these orifices are adjustable, although the invention is not limited to the adjustable feature.

It will now be noted that due to its ability to move up and down the inside of the cylinder 40, the piston 41 will tend to assume a position wherein the gas pressure in the upper compartment 43 is equal to the fluid pressure in the lower compartment 44. By reason of the restricted flow in conduits 28-29, only relatively slow changes in hydraulic pressure are communicated to the chamber 44. Thus the pressure in the chamber 44 is actually an average between the low and high values of the fluid pressure in the hydraulic system which are occasioned by the pressure variations p' . Thus since the pressures in the gas compartment 43 and the fluid compartment 44 are equal, the gas pressure in the compartment 43 is the desired pressure P_{pr} . This pressure P_{pr} is communicated as mentioned, through the duct 30-31 to the gas chamber of

the surge control unit 10. By reason of the addition of the restrictive orifice 33 in the duct 30—31, the relatively high frequency pressure variations in the gas chamber 21 of the surge control unit 10 are not communicated back to the gas chamber 43 of the pressure control unit 11. The piston 41 once it has assumed its position of balance, need not necessarily move until the average working pressure in the hydraulic system changes, and for this reason the walls 40 of the cylinder 11a are not subjected to a large amount of wear or scrubbing action as they would be if the piston 41 moved continually in response to the pressure variation p' .

Turning now to a discussion of an actual structure embodying the principles illustrated in Figure 1, reference should be had to Figure 2. It will be noted in Figure 2 that the operative section of the surge control unit 10, wherein the piston 14 is located, is fabricated as a separate portion of the unit. Said operative portion is comprised of a cylindrical portion 20 formed with attachment flanges 70 and 71 on the lower and upper ends thereof and preferably is only of sufficient length to provide adequate available volume to contain the fluid surge of the system for which it is designed, depending of course, on the type of separatory means used in the unit. In the construction of unit 10, shown in Figure 2, the piston 14 slides on the smooth inner face of the cylindrical portion 20. An obvious alternate structure (not shown) would be to provide a renewable liner within cylinder 20 in which piston 14 might slide and which could be renewed when it became worn beyond a useful limit. The upper section 21 of the control unit 10 is similarly fabricated in the form of a cylinder having flanges 72 and 73. Thus it will be seen that the surge control unit is made up of separate sub-sections which may easily be assembled in various combinations to suit various operating conditions.

The entire surge control unit 10 and the pressure control unit 11 are mounted on a base casting 60 which is provided with a base flange 61 and with flange receiving faces 62, 63, 64, and 65, each of which is adapted to receive an attachment flange of conventional design which may be secured thereto by means of bolts 68.

Passages 25 and 27 are formed within the base casting 60 and a screen device 26 is interposed to screen the hydraulic fluid as it passes through the casting. The accumulator embodying my invention may be interposed in a hydraulic system as indicated in Figure 2 by attachment in a pipeline wherein a flanged pipe 66 constitutes the upstream section and a similar flanged pipe 67 constitutes the downstream section. Sections 66 and 67 are secured to the attachment faces 62 and 63 respectively by means of flange bolts 68 as previously mentioned.

The surge control unit 10 is secured to the upper flange receiving portion 64 and communicated with the hydraulic system through passage 27 formed in the base casting 60. The pressure control unit is similarly attached at the flange receiving portion 65.

The surge control unit 10 and the pressure control unit 11 are provided with upper closures 75 and 82 respectively, which are attached by means of flange bolts 68 to upper flanges 73 and 81, respectively, of the two units.

Located at the bottom of the pressure control unit 11 is a clean-out valve 91 which is mounted in a removable valve seat 90 and is held normally closed by a compression spring 93 acting through

a valve stem 92 and an abutment 94 to hold the valve 91 closed against the seat 90. The purpose of the blow-out valve 91 is to allow the contents of the fluid chamber 44 in the pressure adjustment unit 11 to be discharged through a passage-way 95 directly into the hydraulic system whenever the latter is shut down and the pressure therein drops below that of the precharge pressure. This prevents an accumulation of mud and sand from settling and remaining in the liquid chamber 44 should such foreign matter be present in the hydraulic fluid.

It is contemplated that the minimum operating pressure in any hydraulic system requiring the protection of an accumulator, will be somewhat above atmospheric. For this reason it is necessary that the precharge pressure in the gas chamber of the surge control unit 10 be considerably above atmospheric before operation of the hydraulic system is even started. For the purpose of providing this minimum precharge gas pressure, a gas bottle 46 (shown in Figure 1) containing a gas, preferably but not necessarily nitrogen, under high pressure is communicated through a conduit 45 to the gas chamber 43 of the pressure control unit 11. A valve 49 controls the flow of gas from the bottle 46 into the chamber 43. Should it be desired to disassemble the unit or possibly to lower the lower limit of the operative pressure range, gas may be discharged from the system through a valve 50. Gauges 47 and 48 are provided to indicate the gas pressure in the gas bottle 46 and the pressure control unit 11 respectively.

Figure 3 illustrates an alternative form of surge control element which may in some cases be used in lieu of the element comprising the piston 14 and the diaphragm 16. The piston 130 illustrated in Figure 3 is similar in form to the piston 41 and is provided with packing rings 15 whereby to form a hermetic seal with the walls of the cylinder 20. The piston 130 is supported in an approximately centered intermediate position in the cylinder 20 by means of a pair of springs 131 and 132 respectively which thrust in opposite directions on the upper and lower ends of the piston. The operation of the piston 130 in response to surges in the hydraulic system consists in a vertically reciprocating motion within the cylinder 20. The forces of the springs 131 and 132 are preferably just sufficient to overcome the frictional resistance of the piston 130 and its packing rings 15 against the walls of the cylinder 20. Thus substantially all the resistance to surge responsive motion is produced by the compression of the gas in the chamber above the piston 130 and the piston will more readily cooperate with the compensator to insure optimum results.

In Figure 4 an alternative arrangement of the elements of Figure 1 is illustrated wherein the gas chamber of the surge control unit 10 and that of the pressure compensator are directly connected without any restriction between them. The entire unit is disposed horizontally and is connected in the hydraulic system in such a manner that the surge absorbing element is directly acted upon by the hydraulic fluid, and the pressure compensating piston is responsive to pressure variations at a downstream point in the line. The line is, in effect, by-passed around the accumulator by the pipe 101. If the pipe 101 is of sufficient length and the elements are arranged substantially as shown, little if any restriction may be needed between the downstream side of the line and the pressure compensator. How-

ever, for maximum flexibility of installation I prefer to provide orifice plates 103 of various sizes which can be clamped in place between flange 104 on the conduit 102 and the flange portion 81 of the compensator, the size of the orifice depending upon the characteristics of the system.

As in the form shown in Figure 2, the pressure control unit comprises a cylinder 11a having a smooth bore 40 with a piston 41 slidable therein. The flange 80 of the compensator is bolted to the flange 71 of the surge control unit 10 with the latter being directly connected into the line by bolting its other flange 70 to a flange 105 in a fitting 106 in the upstream line. In this form of my invention, as shown, the cylinder 21 is omitted but it will be understood that it can be inserted between cylinders 29 and 11a if desired, depending upon the line pressure and surge volume to be encountered.

In Figure 4 I have shown a conventional bag type separatory element in the surge control unit instead of the piston type element of Figures 1 and 2. A bag 107 of rubber, neoprene or similar suitable elastic material is sealed at its open end to a base plate 108 having a passage 109 therethrough connecting the bag to the gas chamber 43 of the compensator. The base plate 108 may be conveniently clamped between flanges 71 and 80 as shown. A perforated plate 110, preferably crown in shape, spans the inner end of the passage 27 providing a seat or guard to prevent the bag 107 from blowing out through said passage when the gas pressure inside the bag is considerably greater than the liquid pressure on its outside. A similar perforated plate 99 protects the bag from blowing out through passage 109.

The operation of this form of my invention is substantially the same as the first form, with the bag 107 compressing to absorb sudden surges in the line and the piston 41 varying its position in response to variations in average line pressure to thereby maintain the pressure in the gas chamber and bag at all times equal to the average line pressure.

In Figure 5 a modification of the previously described accumulator is illustrated. In the form of Figure 5 the surge control unit 10 is identical in form and operation to that previously described and shown in Figure 3; however, the pressure control unit 11 of Figures 1 and 2 is replaced by a modified form indicated by the numeral 110. This modified pressure control unit comprises a valve structure 111 which includes a member 112 slidably supported in a cylinder 113. The slideable member 112 is operated through compression springs 114 which in turn abut against flexible diaphragms 115 and 116, respectively. The diaphragms 115 and 116 are supported in the lower and upper ends respectively of the cylinder 113 by end bells 117 and 118 respectively. Hydraulic pressure from the conduit 21 is communicated by a duct 120 to the outer face of the lower diaphragm 115, and gas pressure from the gas chamber 21 is communicated through ducts 121 to the outer face of the upper diaphragm 116. Thus when the pressures in the gas chamber 21 and in the hydraulic system are equal, the slideable member is held by the springs 114 in a central position as illustrated in Figure 5. It will be noted that the interior of the cylinder 113 is in continual communication through slot 124 in the slide member 112, through duct 123 and thence through duct 121 with the chamber 21.

When the gas pressure in the chamber 21 exceeds the hydraulic pressure in the system, the movable diaphragms 115 and 116 and the operation of the compression springs 114 is such as to move the slideable member 112 downwardly, placing a port 126 in the slideable member in alignment with a duct 127 which communicates through a pressure regulator 128 to atmosphere as shown. Thus when the pressure in the gas chamber 21 exceeds the hydraulic pressure, the operation of the valve structure 111 will bleed gas from the chamber 21 until the pressure in said chamber is reduced to that of the hydraulic system.

On the other hand, when the pressure in the hydraulic system rises above that in the gas chamber 21, the operation of the diaphragm 115 and the compression springs 114 is such as to move the slideable member 112 upwardly, placing a port 129 in alignment with the conduit 122, thus to conduct gas from the bottle 46 through the slideable member 112 into the cylinder 113 and out of said cylinder through ducts 123 and 121 into the gas chamber 21 in the surge control unit 10. Thus any variations in hydraulic pressure automatically operate the valve structure 111 to produce an equal pressure in the gas chamber 21.

The pressure regulator 128 is provided in the system in order that the minimum gas pressure in the chamber 21 will never fall below a predetermined amount to which the regulator 128 is adjusted. In this way the lower limit of desired operating pressure range for the hydraulic system may be set by an adjustment of the pressure regulator 128, the upper limit being the pressure of the gas in the bottle 46.

Thus it will be seen that the accumulator structure embodying my invention has the particular advantage, among others, of being universally adaptable to a wide variety of working conditions. It is to be noted in this regard that mud pumps, for example, such as are used in rotary well drilling equipment, are manufactured in a relatively few standard sizes, each of which has a certain cylinder stroke displacement. Consequently, the surge volume S for any given mud pump is known and the surge control unit 10 may be designed in certain sizes, each of which is suitable for use in connection with a particular type and size of mud pump.

The physical dimensions of the pressure compensating unit are not, however, predetermined by the size of the pump only, but must be calculated to accommodate the particular accumulator to the particular range of working pressures that will be encountered. Thus by manufacturing the pressure compensating unit and the surge control unit in a few standard sizes, accumulators can be assembled to suit any combination of pump size and pressure range by selecting the proper units and combining them. This represents a great saving over the methods previously used wherein it was frequently necessary to design and fabricate a complete accumulator for every hydraulic system in which a new combination of factors was encountered.

Another advantage to be gained from the use of apparatus embodying my invention lies in the fact that the principal wear occasioned by surge control takes place in the small and easily replaceable surge unit. As illustrated in Figure 2, to replace this unit it is only necessary to remove the flange bolts 68, slide out the short cylinder 20, drop the piston 14 out through the bottom

of the cylinder, place it in a new cylinder and replace the new cylinder (or a liner therefor) in the unit 10.

Since the motion of the piston 41 in the cylinder 40 takes place only upon a change of the average working pressure of the hydraulic system, such motion is relatively slow and infrequent and the wear on the cylinder 40 relatively small. Thus the replacement of the cylinder 40, while readily achieved, is seldom necessary.

Additionally, it will be apparent that while my system of automatic pressure compensation is particularly well adapted for accumulators of the type shown in my said copending application, it likewise can be applied to all types of accumulators wherein it is desired to change the precharge pressure of the gas in response to the line pressure of the gas in response to line pressure variations. In these latter cases the particular type and design of the compensating element may, of course, be modified to suit the type of surge units being used.

While the various accumulator structures shown and described herein are fully capable of achieving the objects and providing the advantages hereinbefore stated, they are illustrative only of the broad principles of my invention and may be modified by persons skilled in the art without departing from the spirit of the invention. For this reason I do not mean to be limited to the forms shown and described herein, but rather to the scope of the appended claims.

I claim:

1. In a hydro-pneumatic accumulator for cushioning surge pressures in a hydraulic system: a surge control unit having a gas chamber, a liquid chamber in communication with said hydraulic system, and movable separatory means between said gas and liquid chambers; and means responsive to pressure in said hydraulic system to adjust the gas pressure in said gas chamber, said pressure adjustment means including movable separatory means urged in one direction by said hydraulic pressure and in the other direction by pressure of gas in said gas chamber and adapted to selectively compress and decompress gas in said chamber to adjust the pressure therein.

2. A device for adjusting the reactive pressure in a hydro-pneumatic accumulator including: a source of gas under relatively high pressure valved passage means connected between a gas chamber in said accumulator and said source, said valved means having therein a member movable in one direction to discharge gas from said gas chamber and in the other direction to admit gas from said source into said gas chamber; means to reactively communicate the pressure in said gas chamber to a hydraulic system; and movable separatory means exposed on one side to pressure of said gas chamber and on the other side to pressure in said hydraulic system, said separatory means being operatively connected to said movable member whereby when said hydraulic pressure exceeds said gas chamber pressure said member is moved to admit gas from said source into said gas chamber and when said gas chamber pressure exceeds said hydraulic pressure said member is moved to discharge gas from said chamber.

3. In a hydro-pneumatic accumulator: means forming an enclosed vessel having a cylindrical portion; separatory means in an end of said vessel adapted for limited motion in response to hydraulic pressure thereon; second separa-

tory means in said vessel movable in said cylindrical portion in response to exterior hydraulic pressure independently of said first separatory means, said second separatory means having fluid tight contact with interior walls of said cylindrical portion whereby said first and second separatory means and said vessel form an enclosed gas chamber of variable volume depending on the position of said second separatory means; means adapted to communicate a hydraulic system to said vessel ends whereby to apply hydraulic pressure in said system directly to each of said separatory means; and means associated with said communicating means adapted to damp out sudden hydraulic pressure variations in the pressure applied to said second separatory means whereby said first separatory means will cushion said pressure variations in said system by compressing gas in said gas chamber, and said second separatory means will compress gas in said chamber to maintain the average pressure thereof substantially equal to the average working pressure in said hydraulic system.

25 4. In a hydro-pneumatic accumulator for absorbing surges in a hydraulic system, the combination of: means forming a gas chamber having a movable wall, and adapted to be connected in a hydraulic line to place said wall in contact with the fluid in said line whereby said wall will move in response to differentials in pressure between the gas in said chamber and the fluid in said line to balance the same; and means with a movable member forming two compartments of variable volume, one compartment being fluid connected to said gas chamber and the other compartment being fluid connected to said hydraulic line, whereby movement of said movable member in response to differentials in pressure between said two compartments will automatically cause a variation in the pressure in said gas chamber corresponding to the variations in said line pressure.

30 5. In a hydro-pneumatic accumulator for absorbing surges in a hydraulic system, the combination of: means forming a gas chamber having a movable wall, and adapted to be connected in a hydraulic line to place said wall in contact with the fluid in said line whereby said wall will move in response to differentials in pressure between the gas in said chamber and the fluid in said line to balance the same; and means for adjusting the pressure in said chamber in accordance with pressure variations in said line which includes a movable piston urged in one direction by the pressure in said gas chamber and urged in the other direction by the fluid pressure in said line, and adapted upon increase in said line pressure to cause the gas in said chamber to be compressed and upon decrease in said line pressure to allow decompression of said gas.

35 6. In a hydro-pneumatic accumulator for absorbing surges in a hydraulic system, the combination of: a cylinder closed at one end and having its other end adapted to be connected in a hydraulic line; a separatory member movably mounted in said cylinder dividing the same into a liquid chamber in communication with said line and a gas chamber, said member being responsive to sudden pressure variations in said line; a second cylinder closed at both ends; a separatory member movably mounted in said second cylinder to divide the same into a gas chamber and a liquid chamber; passage means

13

communicating said gas chambers; and means providing restricted fluid communication between the liquid chamber of said second cylinder and said line, whereby said second separatory member is responsive only to average line pressure variations.

7. In a hydro-pneumatic accumulator for absorbing surges in a hydraulic system, the combination of: a cylinder adapted to have one end connected in a hydraulic line and its other end also connected in said line but downstream of said first connection; a separatory member in the upstream end of said cylinder mounted for limited movement therein and responsive to variations in upstream fluid pressure in said line; a second separatory member movable in the downstream end of said cylinder and freely movable throughout a major portion of the length thereof and responsive to downstream pressure variations in said line; means for admitting gas under pressure into said cylinder between said separatory members; and means for connecting said cylinder in said line as aforesaid whereby said first separatory member will absorb substantially all of the surge in said line in response to sudden variations in line pressure, and said second separatory member will adjust its position in response to variations in the average line pressure to thereby adjust the gas pressure in said cylinder to said average line pressure.

8. In a hydro-pneumatic accumulator for absorbing surges in a hydraulic system, the combination of: a relatively short surge cylinder open at both ends and adapted to have one of said ends connected in a hydraulic line; a separatory member mounted in said cylinder for limited movement therein and providing a surge liquid chamber in said cylinder; means at the other end of said surge cylinder of substantial size forming a gas chamber on the other side of said separatory member; and separate means fluid connected to said hydraulic line and including separatory means independently movable in response to average pressure variations therein to vary the pressure in said gas chamber in accordance with said average line pressure variations.

9. In a hydro-pneumatic accumulator for cushioning surge pressures in a hydraulic system: a surge control unit having a gas chamber, a liquid chamber in communication with said hydraulic system, and movable separatory means between said gas and liquid chambers; and separate means responsive to pressure in said hydraulic system to adjust the gas pressure in said gas chamber, said pressure adjustment means including independently movable separatory means fluid connected to and urged in one direction by said hydraulic pressure and fluid connected to and urged in the other direction by pressure of gas in said gas chamber whereby to selectively cause the gas in said gas chamber to be compressed and decompressed, one of said fluid connections being such as to restrict the flow of fluid therethrough.

10. In a hydro-pneumatic accumulator for cushioning surge pressures in a hydraulic system: a surge control unit having a gas chamber, a liquid chamber in communication with said hydraulic system, and movable separatory means between said gas and liquid chambers; and separate means responsive to pressure in said hydraulic system to adjust the gas pressure in said gas chamber, said pressure adjustment

14

means including separatory means movable independently of said first separatory means and fluid connected to and urged in one direction by said hydraulic pressure and fluid connected to and urged in the other direction by pressure of gas in said gas chamber whereby to selectively cause the gas in said gas chamber to be compressed and decompressed, the fluid connection between said last mentioned separatory means and said liquid chamber being such as to restrict the flow of liquid therein and thereby cause said separatory member to be primarily responsive to variations in the average working pressure of said hydraulic system.

11. In a hydro-pneumatic accumulator for cushioning surge pressures in a hydraulic system: a surge control unit having a gas chamber, a liquid chamber in communication with said hydraulic system, and movable separatory means between said gas and liquid chambers; and means independent of said separatory means responsive to pressure in said hydraulic system to adjust the gas pressure in said chamber, said pressure adjustment means including a closed cylinder, a piston slideable in said cylinder independently of said separatory means, a first passageway connected between one end of said cylinder and said gas chamber, and a second passageway connected between the other end of said cylinder and said hydraulic system.

12. The construction set forth in claim 11 further characterized by having flow restricting means in said second passageway.

13. In a hydro-pneumatic accumulator for cushioning surge pressures in a hydraulic system: a surge control unit having a gas chamber, a liquid chamber in communication with said hydraulic system, and reciprocable separatory means between said gas and liquid chambers, and resilient means to hold said separatory means in a normally centralized position between limits of its motion; and means responsive to pressure in said hydraulic system to adjust the gas pressure in said gas chamber, said pressure adjustment means including independently movable separatory means urged in one direction by said hydraulic pressure and in the other direction by pressure of gas in said gas chamber and adapted to selectively compress and decompress gas in said chamber to adjust the pressure therein.

14. In a hydro-pneumatic accumulator for cushioning surge pressures in a hydraulic system: a surge control unit having a gas chamber, a liquid chamber in communication with said hydraulic system, and movable separatory means between said gas and liquid chambers; and means responsive to pressure in said hydraulic system to adjust the gas pressure in said gas chamber, said pressure adjustment means including independently movable separatory means urged in a first direction by said hydraulic pressure and in a second direction by pressure of gas in said gas chamber, a source of compressed gas, and valve means fluid connected to said gas chamber and connected to said separatory means whereby motion of the latter in said first direction admits gas from said source into said gas chamber and motion in said second direction discharges gas from said gas chamber.

15. In a hydro-pneumatic accumulator for absorbing surges in a hydraulic system, the combination of: means forming a gas chamber having a movable wall, and adapted to be connected in a hydraulic line to place said wall in contact

with the fluid in said line whereby said wall will move in response to differentials in pressure between the gas in said chamber and the fluid in said line to balance the same; and means for adjusting the pressure in said gas chamber including an independently movable member forming two compartments of variable volume, passage means fluid connecting one of said compartments with said gas chamber and passage means providing restricted fluid communication between the other compartment and said hydraulic line, whereby movement of said movable member in response to differentials in pressure between said two compartments will automatically cause a variation in the pressure in said gas chamber corresponding to the variations in said line pressure.

16. In a hydro-pneumatic accumulator: a base having a passage therein adapted to conduct hydraulic fluid therethrough; an open upright cylinder secured to said base with its lower end in communication with said passage; a separatory member movably mounted in said cylinder having sealing contact with the interior wall thereof and a flexible diaphragm therein to vary the volumetric capacity of said cylinder; limiting means operatively associated with said separatory member adapted to resist volume variations in said cylindrical member greater than a predetermined amount; an enclosed vessel secured to the upper end of said cylinder in communication therewith and adapted to receive and contain gas under pressure whereby to resist said volumetric variations; a second upright cylinder secured to said base member and having communication through a restrictive orifice with said passage; a piston in said second cylinder having fluid tight contact with the wall thereof and movable whereby to divide said second cylinder into chambers of mutually dependent volumes, one of said chambers being a hydraulic fluid chamber with said orifice therein and the other of said chambers being a gas chamber; a closure for the upper end of said second cylinder; and duct means connected between said gas chamber and said vessel to communicate the gas pressure in said gas chamber with the interior of said vessel whereby to adjust the pressure in said vessel in response to motion of said piston.

17. The construction of claim 16 further characterized by having: a relatively large conduit connected from the lowest point in said hydraulic fluid chamber to said passage; and a spring closed check valve in said conduit positioned and adapted to check flow from said passage through said conduit and permit flow from said chamber through said conduit.

18. In a hydro-pneumatic accumulator for absorbing surges in a hydraulic system, the combination of: means forming a gas chamber having a movable wall and adapted to be connected in a hydraulic line to place said wall in contact

with the fluid in said line whereby said wall will move in response to differentials in pressure between the gas in said chamber and the fluid in said line to balance the same; means including a separatory member movable independently of said movable wall forming two compartments of variable volume, one of which is fluid connected to said gas chamber; and duct means communicating the other of said compartments with said hydraulic system and being resistant to high velocity flow therethrough whereby to attenuate sudden pressure variations passing to said separatory member and subject said member principally to the average working pressure in said hydraulic system.

19. In a hydro-pneumatic accumulator for cushioning surge pressures in a hydraulic system: a surge control unit having a gas chamber, a liquid chamber in communication with said hydraulic system, and movable separatory means between said gas and liquid chambers; and means responsive to pressure in said hydraulic system to adjust the gas pressure in said gas chamber, said pressure adjustment means including an auxiliary source of gas under substantial pressure, conduit means connecting said gas source to said gas chamber, valve means in said conduit means, and means fluid connected to said gas chamber and to said hydraulic system and responsive to differentials of pressure therein to operate said valve means in response thereto whereby gas from said source is admitted to said gas chamber when the pressure therein falls a predetermined amount below that in said hydraulic system.

20. Apparatus as defined in claim 19 which includes an escape port and said valve means is formed so as to permit exhaust of gas from said gas chamber when the pressure therein exceeds that of said hydraulic system by a predetermined amount.

21. Apparatus as defined in claim 19 in which said separatory member is restricted in its movement and said gas chamber is of substantial size.

22. Apparatus as defined in claim 19 in which the means for operating said valve means comprises a member movable in a chamber in response to said differential pressures to communicate said valve means with said gas source in response to said pressure differentials.

ROBERT E. SNYDER.
